ALKYLBENZENESULFONATE DETERGENTS
CONTAINING GUANIDINE SALTS OF IN-
ORGANIC ACIDSEmil A. Vitalis, Springdale, Conn., assignor to
American Cyanamid Company, New York,
N. Y., a corporation of Maine

Application April 26, 1949, Serial No. 89,581

6 Claims. (Cl. 252—152)

1

This invention relates to detergent compositions, and more particularly to alkylbenzenesulfonate detergents having greatly improved wool-scouring properties.

Synthetic detergents of the alkylbenzenesulfonate type are well known and are in wide commercial use. They are the sulfonation products of mononuclear aromatic hydrocarbons containing a single long alkyl radical, usually of about 10-16 carbon atoms, with or without one or two additional short chain hydrocarbon substituents on the benzene nucleus. The hydrocarbons of this type are ordinarily prepared by one of two methods; either by condensing an olefin of about 10-16 carbon atoms such as a propylene or butylene polymer with benzene, toluene or xylene, or by condensing any one or more of these aromatic hydrocarbons with a chlorinated kerosene fraction of 10-16 carbon atoms, usually with the aid of an aluminum chloride catalyst. The resulting alkylbenzene compound is sulfonated by well known sulfonation procedures, usually by employing oleum containing 10% to 30% of free sulfur trioxide at temperatures of about 10-30° C.

The sulfonation of the alkylbenzene compounds is usually carried out with an excess of acid, about 3-4 mols of acid per mol of alkylbenzene compound being used. After the sulfonation is complete the mixture is ordinarily neutralized with a water-soluble alkali such as sodium, potassium or ammonium hydroxide, which produces a mixture of the alkylbenzenesulfonate detergent with approximately 50-200% of its weight of sodium sulfate, potassium sulfate or ammonium sulfate. It has been proposed to neutralize the sulfonation product with lime, followed by reaction with sodium or potassium carbonate to remove the calcium and produce a purified product containing only relatively small amounts of alkali metal or ammonium sulfate. However, this procedure is not ordinarily employed in commercial manufacturing processes. It has also been proposed to purify the sulfonated product by extraction with organic solvents, which results in the removal of unsulfonated hydrocarbons and tarry impurities and also removes the alkali metal sulfate.

The alkylbenzenesulfonate detergents of the above-described class are effective for the washing of cotton cloth and other cotton textiles, but for some unknown reason they are not as good on wool. It is a principal object of the present invention to improve the detergency of this class of compounds for woven and knitted wool or wool-containing textiles by the addition

thereto of a water-soluble guanidine salt. I have found that a mixture of an alkylbenzenesulfonate detergent of the above-described class with from about 2% to about 50% of its weight of guanidine salt possesses greatly improved scouring properties for wool and woolen textiles, and when the guanidine salts are used in quantities of from about 10-15% to about 25-40% the detergency on wool is increased some 5 to 6 times.

10 This discovery is quite surprising, since the guanidine salts themselves possess little or no detergency for wool.

The addition of guanidine carbonate to the alkylbenzenesulfonate detergents also improves 15 the storage properties of the composition, and therefore this is the preferred guanidine salt for use in practicing the invention. Many of the alkylbenzenesulfonates are quite hygroscopic; moreover, they tend to liquefy after absorbing 20 moisture from the atmosphere, and will therefore form a sticky mass unless they are stored in containers which are completely air-tight. Although the presence of 50-200% of their weight of sodium sulfate, sodium chloride or other in- 25 organic salt will improve their storage properties the mixtures still have a strong tendency to cake when exposed to a moist atmosphere. I find that the presence of guanidine carbonate will assist materially in maintaining the composition in a dry and free-flowing condition. When the 30 above-indicated amounts of inorganic salt are present this is accomplished by about 7-15% or more of guanidine carbonate, based on the weight of the alkylbenzenesulfonate; a similar 35 result is obtained when about 30-50% of guanidine carbonate is mixed with a purified alkylbenzenesulfonate detergent containing little or no sodium sulfate or other inorganic salt.

Although any of the alkylbenzenesulfonate 40 detergents described above may be improved by admixture with guanidine salts, the preferred compositions of my invention are those in which an alkyltoluenesulfonate is employed. These preferred compounds are best described by the formula

45 in which R is an alkyl radical of 10-16 carbon atoms, and preferably one of about 12-14 carbon atoms. As will subsequently be shown these alkyltoluenesulfonate detergents, when admixed with 2-50% of their weight of guanidine carbonate or sulfate, possess excellent detergency

for wool, and also possess good stability on storage.

Any water-soluble guanidine salt may be used to obtain an improved detergency of the alkylbenzenesulfonates on wool, although for most practical purposes the guanidine salts of inorganic acids are preferred. Typical of these are guanidine nitrate, guanidine hydrochloride, guanidine sulphate, guanidine phosphate, and the guanidine carbonate referred to above. However, the corresponding water-soluble salts of organic acids may be used if desired, and particularly such compounds as guanidine acetate, guanidine benzoate, guanidine phthalate, guanidine carbonate and guanidine anthranilate.

My invention will be described in greater detail by the following specific examples, and with reference to the accompanying drawing. In this drawing the single figure is a graph showing the detergency of alkyltoluenesulfonate-guanidine carbonate and -guanidine sulfate mixtures on wool.

Example 1

An alkyltoluenesulfonate prepared by condensing toluene with a propylene polymer fraction and having an average composition of $\text{CH}_3\text{C}_6\text{H}_4\text{C}_{12}\text{H}_{25}$ was sulfonated with 20% oleum. The sulfonation was carried out by adding the oleum to the hydrocarbon, using a 4:1 molar ratio and maintaining the temperature of the mixture at 15-25° C. Under these conditions the formation of the monosulfonate was complete in about 0.5-3 hours.

One portion of the sulfonation mixture was purified by the process described in U. S. Patent No. 2,433,316. A small amount of water was added and the product was then extracted with toluene. The resulting toluene solution of the sulfonic acid was separated from the residue and agitated with 2-3 times its volume of water followed by neutralizing with 40% sodium hydroxide solution and evaporation on a steam bath. This produced a purified sodium alkyltoluenesulfonate containing only a small quantity (about 5%) of sodium sulfate.

The remainder of the sulfonation mixture was neutralized by pouring it into a slight excess of sodium hydroxide solution of 15-20% concentration. This produced a slurry of approximately 35% solids, of which about 45-50% was sodium alkyltoluenesulfonate and about 50-55% was sodium sulfate. This slurry was dried to flake form on a steam-heated drum dryer.

Varying amounts of guanidine carbonate and of guanidine sulfate were mixed with the alkyltoluenesulfonate-sodium sulfate mixture prepared by the second of the two methods described to produce compositions containing from 0.1% to 100% of guanidine carbonate and from 0.1% to 55% of guanidine sulfate, these percentages being based on the weight of the alkyltoluenesulfonate in the detergent mixture.

The detergency of the products was determined with the aid of a "standard soil" having the following composition:

	Grams
Carbon black	0.75
White mineral oil	3.00
Lard	3.00
Carbon tetrachloride to make 3 liters.	70

Wool cloth was passed through this solution and held vertically, allowing the excess liquor to drain. During this period the fabric was inverted several times to insure uniform distribu-

tion of the soil while the solvent evaporated and the fabric was then air dried at room temperature. The impregnation and drying was repeated for a total of four times after which the fabric was cut into four inch squares. Reflectance measurements were taken of these squares at 600 millimicrons on a G. E. Recording Spectrophotometer.

Detergency tests were run at 0.1% concentration of sodium alkyltoluenesulfonate in the Launderometer according to A. A. T. C. C. procedure. Into each pint jar were placed 20 one-fourth inch glass beads, 200 ml. of the detergent solution under test, and one numbered soiled swatch. The jars were rotated at 42 R. P. M. in the machine at 110° F. for 20 minutes and this was repeated for a total of 3 times using fresh detergent solution for each wash. The third wash was followed by three five minute rinses. The cloth pieces were then squeezed, ironed dry, and again measured for reflectance in the spectrophotometer. The percent of return of the cloth to its original reflectance, prior to application of the soil, is the measure of detergency.

The results obtained are shown on the attached drawing. When no guanidine salt was added the detergency value was about 8 to 10%. This value increased to about 20% upon adding 2% of the guanidine salt and continued to increase with further guanidine salt additions until maxima were reached at 25% guanidine sulfate and about 37% guanidine carbonate content, after which the detergency decreased to a constant value at about 50% guanidine salt content. The constant detergency obtained with 50% or more is about equal to that obtained with 2% of the guanidine carbonate or sulfate; therefore, the detergency of the alkyltoluenesulfonate is doubled by adding any quantity of guanidine salt between 2% and 50% or more and is increased more than five times by amounts of from about 10% to about 45%.

Similar tests using 0.25% aqueous solutions of guanidine carbonate and of guanidine sulfate containing no alkyltoluenesulfonate gave detergency values of 2, showing that these salts possess practically no detergency when used alone.

Example 2

Varying quantities of guanidine carbonate were mixed with an alkylbenzene sodium sulfonate prepared by condensing benzene with a propylene polymer fraction ranging from C_1H_{22} to about $\text{C}_{14}\text{H}_{30}$ and having an average molecular weight of 168 and sulfonating the product as described in Example 1. The sulfonation mixture was neutralized by pouring it into a 20% aqueous sodium hydroxide solution and the guanidine carbonate was added to the resulting slurry which was then drum dried.

The detergency values were determined by the method described in Example 1 and were as follows, the percent of guanidine carbonate being based on the weight of the alkylbenzene sodium sulfonate.

Percent Guanidine Carbonate	Detergency on Wool
0	6
12.5	17
20	26
25	37
37.5	48
50	13

Example 3

Another advantage obtained with guanidine carbonate when admixed with the alkylated mononuclear arylsulfonate detergents is a marked reduction in hygroscopicity. Many of the detergents of this class have a tendency to liquefy by reason of moisture absorbed from the air, which is one of the reasons why they are usually sold as a mixture with sodium sulfate. Even the presence of this salt, however, does not prevent them from caking on storage. I have found that the presence of even small quantities of guanidine carbonate will maintain a sodium sulfate-containing product in a free-flowing condition under ordinary storage conditions and that larger quantities will protect a purified product in similar manner.

Samples of the unpurified material of Example 1, containing about 45% of alkyltoluenesulfonate and 55% of sodium sulfate, were stored in open containers under varying conditions of relative humidity. One set of samples was used as a control while 5-12% of guanidine carbonate based on the weight of the alkyltoluenesulfonate (2-5% on the weight of the mixture) was incorporated uniformly in the others. The compositions were then stored in open containers under the conditions shown in the following table.

Additive	Per Cent	Appearance After Storage		
		Room Conditions 2 Months	65% R. H. -25° C. 2 Months	90-100% R. H.-30° C. 4 Days
None				
Guanidine Carbonate	5	Caked	Wet Lumps	Liquid
Do	7	Dry Powder	Slightly Damp	Do
Do	12	do	Dry Powder	Do
			do	Wet Solid

A similar test was made on the purified material described in Example 1. Mixtures with guanidine carbonate were prepared and stored in open containers at 65% relative humidity and 70° F. In the following table the quantities are parts by weight.

Na Alkyltoluenesulfonate	95	85	70	50
Guanidine Carbonate	5	15	30	50
Appearance After Storage	Lumped	Lumped	Dry Powder	Dry Powder

These results show that the ordinary commercial mixtures containing about equal parts of an alkylbenzenesulfonate detergent and sodium sulfate are protected against adverse storage conditions by a content of 5-12% or more of guanidine carbonate, based on the weight of the alkylbenzenesulfonate, and that 30-50% or more will give similar protection to a purified material.

Example 4

Test samples containing a number of different guanidine salts were prepared from an alkyltoluenesulfonate produced from a commercially available alkyltoluene fraction having an A. S. T. M. distillation boiling range (5 to 95%) of 289°-304° C. and an average molecular weight (cryoscopic) of 268. This alkyltoluene was sulfonated and neutralized with aqueous sodium hydroxide solution by the procedure described in Example 1.

Mixtures were prepared from this material having the following composition, the parts being by weight:

Alkyltoluenesulfonate	40
Sodium sulfate	55
Guanidine salt as indicated below	5

These samples were tested for dexterity on wool by the procedure described in Example 1 with the following results:

	Guanidine salt	Dexterity
10	carbonate	58
	hydrochloride	48
	nitrate	50
	phosphate	47
	sulfate	50
15	none	16

What I claim is:

1. A composition consisting essentially of a detergent mixture of 98% to 50% by weight of a member of the group consisting of sodium, potassium and ammonium salts of an alkylbenzenesulfonate containing a single long alkyl radical of 10-16 carbon atoms and 2% to 50% of a water-soluble guanidine salt of an inorganic acid.
2. A composition consisting essentially of a detergent mixture of 98% to 50% by weight of an alkyltoluenesulfonate of the formula

in which R is an alkyl radical of 10-16 carbon atoms and 2% to 50% of a water-soluble guanidine salt of an inorganic acid.

3. A composition consisting essentially of a detergent mixture of 98% to 50% by weight of a member of the group consisting of sodium, potassium and ammonium salts of an alkylbenzenesulfonate containing a single long alkyl radical of 10-16 carbon atoms and 2% to 50% of guanidine carbonate.

4. A composition consisting essentially of a detergent mixture of 98% to 50% by weight of an alkyltoluenesulfonate of the formula

in which R is an alkyl radical of 10-16 carbon atoms and 2% to 50% of guanidine carbonate.

5. A composition consisting of 98 to 50 parts by weight of a member of the group consisting of sodium, potassium and ammonium salts of an alkylbenzenesulfonate containing a single long alkyl radical of 10-16 carbon atoms, 2 to 50 parts of guanidine carbonate, and about 200 to 50 parts of sodium sulfate.

6. A composition consisting essentially of a detergent mixture of 98% to 50% by weight of an alkylarylsulfonate of the formula

in which X is a member of the group consisting of hydrogen and the $-\text{CH}_3$ radical, M is a monovalent salt-forming radical selected from the 75 group consisting of sodium, potassium and am-

monium and R is an alkyl radical of 10-16 carbon atoms and 2% to 50% of a water-soluble guanine salt of an inorganic acid.
